COMPRESSOR UNLOADING VALVE
MECHANISMBurns Dick, Ferguson, Mo., assignor to Wagner
Electric Corporation, St. Louis, Mo., a corpora-
tion of Delaware

Application November 8, 1939, Serial No. 303,378

5 Claims. (Cl. 230—31)

My invention relates to compressors and more particularly to valve mechanism for unloading the compressor under certain conditions.

One of the objects of my invention is to provide an improved valve mechanism for automatically unloading a compressor when the fluid compressed thereby and discharged into a receiver is a predetermined value.

Another and more specific object of my invention is to embody electrical-operated control means in the compressor unloading valve mechanism to thereby facilitate the installation of the control valves which form a part of the mechanism and also lower the cost of manufacture.

Other objects of my invention will become apparent from the following description taken in connection with the accompanying drawings in which Figure 1 is a view, partly in section, of a compressor having associated therewith an unloading valve mechanism embodying my invention and Figure 2 is a view, partly in section, showing a modified unloading valve mechanism.

Referring to the drawings in detail, the rotary compressor is of known construction and comprises a stator 1 having eccentrically mounted therein a rotor 2 secured to a drive shaft 3 journaled in the end plates 4 and 5. The rotor 2 is provided with a plurality of spaced slots extending in an axial direction in which are mounted reciprocable blades 7 (one only being shown) biased outwardly into engagement with the inner surface of the stator by springs 8. The end plate 4 is provided with an intake passage 9 and the end plate 5 with an outlet passage 10. Secured to the end plate 5 is an oil reservoir or dome 11 which contains oil for the purpose of lubricating the compressor. In the construction shown the shaft 3 of the compressor drives an oil pump 12 to pump oil from the body of oil through passage 13 and discharge it into a well 14 through the opening 15. The oil in the well is free to flow through the passage 16 in shaft 3 and then into the compressor by way of the keyway 17 to thus provide lubrication for the movable parts of the compressor. In order that the oil may be forced into the compressor under pressure during operation of the compressor, the body of oil in the oil dome is caused to be subjected to the fluid under pressure discharged from the compressor. This is accomplished by having the discharge port 10 connected to a pipe 18 which extends above the oil line. An oil separator 19 removes any excess oil which may be discharged from the compressor together with

the compressed air. The discharge port 10 has associated therewith a check valve 20 for preventing any of the compressed air from returning to the compressor. The oil dome communicates with the compressed air receiver or tank 21 by a conduit 22 and a check valve 23 prevents return of compressed air to the dome. The compressed air may be used for any purpose desired, as for example, the actuation of vehicle brakes.

In the type of compressor just described the 10 compressor is generally automatically unloaded by shutting off the intake when the receiver for the compressed air discharged by the compressor reaches a predetermined value and again allowed to compress air when the compressed air in the 15 receiver falls to a given pressure below the predetermined value. With such an arrangement, it has been discovered that when the compressor is unloaded an excess amount of oil may be fed to the compressor and cause it to become 20 "choked" because of the compressed air acting upon the oil and forcing it into the compressor. It has also been discovered that the shutting off of the compressor by closing the intake 25 does not cause the compressor to run idle 25 since the compressor still operates to compress the air remaining in the compressor which may be partially discharged into the oil dome against the compressed air already therein or, if this is not accomplished due to insufficient air to compress, recirculated and recompressed continuously. By the compressor being partially under load and performing work, it will continue to generate heat and use power, notwithstanding no additional compressed air is being added to the receiver. All of these undesirable operating features present when the compressor intake is shut off can be eliminated to a large extent by also unloading the oil dome at the same time the intake is shut off. With the air in the oil dome 30 under atmospheric pressure, the oil forced into the compressor will be reduced and the air and oil being circulated in the compressor will be free to be discharged into the oil dome against atmospheric pressure instead of against compressed air. A superior operating compressor 35 results which will require less power to operate when no air is required to be compressed. Also the compressor will operate at a much cooler temperature, less oil will be used, and the life 40 of the compressor extended.

My improved valve mechanism for shutting off the intake and opening the oil reservoir to atmosphere comprises a casing 24 provided with intercommunicating passages 25 and 26, the 55

former being connected to the inlet passage 9 and the latter to the atmosphere through the air cleaner 21. Associated with passage 25 is a valve seat 28 and cooperating therewith is a valve member 29 positioned in an enlarged chamber 30 between the passages 25 and 26. The valve member 29 is normally biased to an open position by a light spring 31.

The casing of the valve mechanism is also provided with a chamber 32 which is connected to the top of the oil reservoir or dome 11 by a conduit 33. The chamber 32 communicates with passage 26 by means of a passage 34 which has associated with its end a valve seat 35 and cooperating with this seat is a valve element 36 positioned in chamber 32 and normally held upon the seat by spring 37. Between the chamber 32 and the passage 25 is a bore 38 in which is guided an extension 39 carried by the valve member 29. The extension is of such length that when the valve member 29 is in open position, the valve member 36 will be held seated by its spring and when the valve member 29 is moved to closed position, the extension 39 will force the valve member off its seat and place chamber 32 (and also the oil reservoir 11) in communication with atmosphere through passage 34.

In order that the valve member 29 may be moved to closed position and the valve member 36 to open position when the pressure in the receiver 21 is a predetermined value, there is provided a solenoid 40, the winding 41 of which is connected to the valve member 29. One end of the winding is connected to ground by a conductor 43 and the other end is connected by a conductor 44 to one side of the battery 45, the other side being connected to ground by conductors 46 and 47 through a pressure-operated switch 48. This switch comprises a fixed contact 49 connected to the conductor 47 and a movable contact 50 connected to the conductor 46. The movable contact is carried on a diaphragm 51 which is biased by a spring 52 to a position where the contacts 49 and 50 will be normally disengaged. The diaphragm 51 forms with the housing 53 of the switch, a chamber 54 which is in constant communication with the compressed fluid in the receiver 21 by a conduit 55. Spring 52 for the switch is of such strength that it will maintain the contacts separated until a predetermined pressure is present in the receiver of the chamber 54. For the purpose of this description, this pressure is considered as one hundred pounds per square inch.

When the compressor is operating, the parts of the valve mechanism and the switch are in the position shown in Figure 1. Under these conditions the valve element 29 will be open and the valve member 36 will be closed. This will permit air to be drawn into the compressor where it is compressed and forced out through the check valve 20 into the oil reservoir 11 and then through the check valve 23 into the receiver 21. When the compressor has operated sufficiently to bring the pressure in the receiver to the assumed predetermined value of one hundred pounds per square inch, the contacts 49 and 50 of the switch will be closed by movement of the diaphragm against the action of spring 52. Closing of the switch will energize the solenoid 40 and cause its armature to move the valve member 29 to the left, thereby shutting off the intake passage to the compressor. Simultaneously with the movement of the valve member 29 to closed position, the valve member 36 will be moved off

its seat and thereby place the oil reservoir in communication with atmosphere and cause the pressure in the reservoir to drop to atmospheric pressure. The compressor now will be substantially completely unloaded. Any air which may be in the compressor will be easily forced out through the check valve 20 into the oil dome and from there into atmosphere since it is not necessary for the air being compressed to move the outlet valve 20 off its seat against any built-up pressure. There may be a slight leakage of air in the compressor around the extension 39 but this air will be easily circulated through the compressor forced out through the outlet valve with very little compressing operation. The connecting of the oil reservoir to atmosphere also results in placing the oil in the oil well 14 under atmospheric pressure and the only oil which will flow into the compressor will be that which flows under the action of gravity and that which is pulled in as a result of sub-atmospheric pressure in portions of the compressor. The flow of oil will be so decreased that the compressor will not tend to "choke" up as would be the case if the intake were shut off and the pressure in the oil dome not relieved. Since the compressor is now running idle and not performing any compressing operation, the power necessary to turn the rotor is a minimum and the heat being generated by the compressor is also a minimum. Consequently, the compressor will have an opportunity to cool as will also the oil in the reservoir. The result is a more efficiently operating compressor and one in which the life is considerably extended.

When fluid under pressure is used from the air receiver and the pressure therein drops to such a value that spring 52 of the switch can open the contacts thereof, the solenoid will be de-energized and the valve member 29 moved to an open position by spring 30. Simultaneously with the opening of the valve member 29, the valve member 36 will be closed, thereby again sealing the oil reservoir. The compressor can now begin to compress air and again force it into the air receiver to thereby bring the pressure of the air in the receiver up to the predetermined value of one hundred pounds per square inch.

In Figure 2 there is shown a modified valve mechanism for shutting off the intake of the compressor and venting the oil reservoir to atmosphere. In the figure the parts similar to those disclosed in Figure 1 have the same reference characters. The valve mechanism comprises a casing 56 having therein two communicating bores 57 and 58, the latter of which communicates directly with the intake passage 9 of the compressor and the former of which communicates with atmosphere by means of a passage 59 and the air cleaner 60. At the juncture of the two bores 57 and 58 there is provided a valve seat 61 and cooperating therewith is a valve member 62 which is normally biased off seat 61 by a spring 63, the tension of which is adjustable by the nut 64. The valve member 62 is provided with an extension 65 which is guided in a sleeve 66 carried by a member 67 of insulating material. The extension 65 abuts against a diaphragm 68 which is held in sealed engagement with the valve casing by a cap 69. The chamber 70 above the diaphragm is placed in communication with the air receiver by a conduit 71.

The oil dome 11 is provided with a vent passage 72 which is connected to atmosphere through the air cleaner by a conduit 73. Associated with the vent passage is a valve seat 74

and cooperating therewith is a valve member 75 having connected with its stem a plunger 76 forming the armature of a solenoid 77. This plunger is biased by a spring 78 to a position to hold the valve member 75 seated. One end of the winding 79 of the solenoid is grounded and the other end is connected by a conductor 80 through a battery 81 to the valve member 62 which is made of conducting material and forms one of the contacts of a switch. The other contact for this switch is the valve seat 61 formed on the valve casing which is also made of conducting material. The circuit is completed by connecting the valve casing to ground by a conductor 82. In order that the valve 62 may be completely insulated in the valve casing, an insulating member 83 is interposed between the spring 13 and the valve element. As already mentioned, the guide sleeve 66 is insulated from the casing by the member 67.

When the compressor is operating, the parts are in the position shown in Figure 2. The tension of spring 53 is such that the valve member 62 will not be moved to closed position until one hundred pounds per square inch pressure is present in the air receiver and also chamber 70 above the diaphragm. When the air receiver reaches the pressure of one hundred pounds per square inch, the valve member 62 will be moved to closed position and shut off the intake of the compressor. The suction of the compressor will now be effective to assist the holding of the valve member on its seat. As the valve member 62 engages the seat, the electrical circuit is closed. The closing of the switch energizes the solenoid 77 and causes the plunger 76 to move the valve member 75 off its seat, thereby placing the oil reservoir in communication with the atmosphere and dropping the pressure therein. The compressor will then be substantially completely unloaded.

When compressed air in the receiver is used and the pressure therein drops to such a value that the spring 63 can again open the valve member 62 against the forces tending to hold it closed, the compressor will again begin to operate to compress air. As the valve member 62 is unseated, the electrical circuit will be broken and the valve member 75 closed by the spring 78, thereby sealing the oil reservoir and resulting in the compressed air discharged therein flowing directly to the air receiver.

By employing electrical means for controlling either one or both of the valves of the unloading valve mechanism, installation thereof is facilitated. In the construction shown in Figure 1, the switch can be placed in any convenient place and no problem is employed in connecting the switch in circuit with the solenoid. In the construction shown in Figure 2, the valve for venting the oil reservoir can be made separate from the intake shut-off valve and mounted at a distance therefrom directly on the reservoir casing. A single fluid motor can be employed for controlling both valves, thus minimizing the cost.

Being aware of the possibility of other modifications in the particular structures herein described without departing from the fundamental principles of my invention, I do not intend that their scope be limited except as set forth by the appended claims.

Having fully described my invention, what I claim as new and desire to secure by Letters Patent of the United States is:

1. In compressed air storage apparatus comprising a receiver and an air compressor provided with intake and discharge ports, a normally open intake valve, a normally closed valve for placing the discharge port in communication with the atmosphere, and automatically operable means for closing the intake valve and substantially simultaneously opening the second named valve when the fluid pressure in the receiver reaches a predetermined value, said means comprising a solenoid for controlling at least one of said valves, an electrical circuit for the solenoid, and a switch caused to be closed when the pressure in the receiver reaches said predetermined value.

2. In compressed air storage apparatus comprising a receiver and an air compressor provided with intake and discharge ports, a normally open intake valve, a normally closed valve for placing the discharge port in communication with the atmosphere, means for operatively connecting the valves together so that when the first named valve is closed the second named valve will be open, a solenoid for controlling said valves, an electrical circuit including a switch for causing operation of the solenoid, and means for closing the switch when the pressure in the receiver is a predetermined value.

3. In compressed air storage apparatus comprising a receiver and an air compressor provided with intake and discharge ports, an intake valve resiliently biased to an open position, a second valve resiliently biased to closed position and capable of connecting the discharge port to atmosphere, the movable elements of said valves being in axial alignment, a rod operatively connecting the movable valve elements, a solenoid for closing the intake valve and by means of the rod cause the second valve to be open, and an electrical circuit for energizing the solenoid including a normally open switch, and a fluid motor connected to close the switch when the receiver pressure reaches a predetermined value.

4. In compressed air storage apparatus comprising a receiver and an air compressor provided with intake and discharge ports, a normally open intake valve, a normally closed valve for placing the discharge port in communication with the atmosphere, a fluid motor for closing the intake valve when the pressure in the receiver reaches a predetermined value, a solenoid for opening the second named valve, and an electrical circuit including a switch for energizing the solenoid, said switch being so associated with the fluid motor that it will be moved to closed position by the fluid motor simultaneously with the closing of the first named valve.

5. In compressed air storage apparatus comprising a receiver and an air compressor provided with intake and discharge ports, a normally open intake valve, said valve comprising a seat and a movable valve element made of electrical conductive material, a normally closed valve for placing the discharge port in communication with the atmosphere, a fluid motor for closing the intake valve by seating the movable valve element when the pressure in the receiver reaches a predetermined value, a solenoid for opening the second named valve and an electrical circuit for energizing the solenoid and including the valve seat and the movable valve element as a switch.

BURNS DICK.
